UNITED STATES PATENT OFFICE.

HARRY H. CHINSKY AND EMIL HONSTETTER, OF BROOKLYN, NEW YORK.

SPARK PLUG.

Application filed April 10, 1920. Serial No. 372,823.

To all whom it may concern:

Be it known that we, HARRY H. CHINSKY, a citizen of the United States, residing in Brooklyn, county of Kings, and State of New York, and EMIL HONSTETTER, a citizen of the United States, residing in Brooklyn, county of Kings, and State of New York, have invented certain new and useful Improvements in Spark Plugs, of which the following is a specification.

The objects of this invention are to provide a jump spark plug in which the spark is intensified due to the gap or space in its path of travel and delivered with an increased effect.

A further object is to provide means for adjusting the relative distance between the contacts and also the length of gap through which the current passes.

Another object is to provide a transparent casing obtaining a "sight feed" effect whereby the spark in passing from one portion to another of the conductor is plainly visible, and to provide means for cushioning and heat insulating the casing.

These objects are attained by the novel construction and combination of parts hereinafter described and shown in the accompanying drawings forming a material part of this disclosure, and in which:—

Figure 1 is a front elevational view showing a spark plug made in accordance with the invention.

Figure 2 is a vertical sectional view taken through the center of the same.

Figure 3 is a transverse sectional view taken on line 3—3 of Fig. 2.

Referring to the drawings in detail, the numeral 10 designates the metallic body of the plug, the same having a reduced step 11 from which extend a screw threaded stem 12 engageable in the motor head or like part where sparks are desired.

The upper portion of the body is surrounded by a hexagonal head 14 suited to receive a wrench in engaging the body in operative position.

Within the body is a curved conoidal chamber 15, its larger part being uppermost, while its lower, smaller end registers with a cylindrical passage 16 through the stem 12.

The head 14 contains an interiorly threaded chamber 17, communicating with the opening 15, and to which is fitted the threads of an annular ring 19 formed with the cap 20 having a hexagonal exterior and

containing, in its lower portion, screw-threads receptive of a clamp ring 22, and the upper part of the cap is formed to present an inwardly extending ring or seat 23. 60

A porcelain insulator 25 is formed with a body portion suited to the conoidal chamber 15 and a cylindrical upper portion 26, the same rising from the inverted base 27 of the insulator, which is level with the bottom 65 of the chamber 17, and disposed over these surfaces is a washer 28 clamped by the ring 22.

Formed with the ring 22 is an upwardly and inwardly curved casing 30, terminating in a raised hexagonal element 31 containing a central opening for the portion 26 of the insulator. 70

This insulator has a central longitudinal passage to which is fitted a metallic sleeve 75 32, threaded interiorly to receive, in its lower portion, a stem 33 which extends downward into the opening 16 and is provided with a spherical terminal 34, which, due to its screw threaded stem, may be adjusted relative to the fixed terminal 35 set rigidly in the lower end of the stem 12. 80

The upper end of the sleeve 32 receives in a similar manner another stem 37, having a spherical head 38. 85

A transparent glass casing 40 is formed with an expanded, curved base 41, the same resting on an annular seat formed with the casing 30, a packing ring 42 of asbestos being interposed between, while between the element 41 and seat 23 is a similar packing 90 43.

Thus as the cap 20 is tightened in the body of the plug, the casing 40 is tightly but yieldingly held and due to the asbestos being a non-conductor of heat, breakage of the glass is prevented. It will also be seen that upon clamping the casing 40, the washer 28 and insulator are also firmly secured in position. 95

The upper end of the casing 40 is contracted in the manner of an ordinary glass bottle and provided with a cap 45 having a neck 46 engaging a head 47 drilled and suited to receive a stem 49 which may be clamped by the lock nut 28, and which, at its inner end, carries a spherical head 50 registering with the head 38, the arrangement being such that these heads are relatively adjustable as to distances apart, thereby controlling the length of the spark as it passes between. 100 105 110

It will be understood that the usual electrical connections are made with the extending stem 49 and body 10, and that the general assemblage is of the usual character as 5 is also the purpose of the invention.

Having thus described our invention and set forth the peculiar manner of its construction and improvements embraced therein, what we claim as new and desire to secure 10 by Letters Patent, is:—

A spark plug comprising a body, an insulator therein, a ring above said insulator, a glass casing, means for clamping said casing

to said ring, non-conducting, yielding packings between said casing and said ring, a 15 sleeve in said insulator, a sectional conductor in said sleeve, each section being independently adjustable longitudinally, a fixed terminal at the inner end of said body, and an adjustable terminal engaged at the 20 outer end of said casing.

In testimony whereof we have signed our names to this specification.

HARRY H. CHINSKY.
EMIL HONSTETTER.
